[57] CLAIM

The ornamental design for a bottle cap snipper, as shown and described.

DESCRIPTION

FIG. 1 is an isometric view of a bottle cap snipper showing my new design;

FIG. 2 is a front elevational view thereof;

FIG. 3 is a right side elevational view thereof, the left side being identical;

FIG. 4 is a rear elevational view thereof;

FIG. 5 is a top plan view thereof;

FIG. 6 is a bottom plan view thereof; and

FIG. 7 is an isometric view thereof in an open position.
